COMPRESSOR WITH OPPOSED PISTONS

Erwin Waeber, Winterthur, Switzerland, assignor to Sulzer Frères, Société Anonyme, Winterthur, Switzerland

Application December 30, 1941, Serial No. 424,861
In Switzerland June 13, 1941

3 Claims. (Cl. 230—172)

The invention relates to a compressor with opposed pistons, particularly a scavenging pump or a charging compressor for two-stroke opposed-piston internal combustion engines. The invention provides each piston with a central guide means at the end facing its opposed piston and a partition separating the adjacent working spaces of the two opposed pistons and having one column on each of its opposite faces which engages the central guide means of the pistons.

Preferably the adjacent working spaces of two opposed pistons are separated from each other by a partition which is fitted on each face with a column on which the piston slides. This partition may be formed of two disks which are held against each other, with at least one ring inserted between them in a groove of the cylinder wall. It will be found preferable to give the rings a curved cross-section, so that they are deformed when the partition is put together.

Each piston may further be guided by a trunk piston extension at the end away from the opposed piston. Thereby the column guiding the piston may project within the trunk piston extension. Under certain circumstances also the partition may be formed with perforations so that the working spaces of the two pistons are connected to each other. The partition may be used as a displacer so that the clearance may be reduced to a minimum.

The accompanying drawings illustrate embodiments of the invention, in which:

Fig. 1 shows a compressor according to the invention. Fig. 2 shows a detail of the compressor to a larger scale.

In the compressor cylinder wall 1 the pistons 2 and 3 are moved in opposite directions by the cranks 4 and 5. The medium to be compressed then flows from the suction space 6 through the suction valves 7 into the cylinder and after being compressed passes through the delivery valves 8 into the pressure space 9.

Between the adjacent working spaces 10 and 11 is the partition 12, which possesses columns 13 and 14 respectively on the two faces for guiding the pistons 2 and 3. The partition is formed of two disks which are held together by the bolts 15. In the groove 16 (Figs. 1 and 2) of the cylinder wall, the rings 17, made in several parts and slightly curved, are inserted without any gaps. When the two disks are drawn together, these rings are deformed in such a way that they not only ensure the partition being securely fixed,

but also make a tight joint between working spaces 10 and 11.

The pistons 2 and 3 are each fitted with a trunk piston extension 18 and 19 respectively at the end away from the partition, and this, together with the column, on which the piston slides, serves to guide the piston; it has a bolt for the connecting rod between the pistons and the crank. In this way a particularly compact form of construction is obtained, since the columns 13 and 14 project into the trunk piston extensions 18 and 19 respectively.

The partition is of such a shape that it is simultaneously used to act as a displacer, since clearance is reduced to a minimum and the compressed air can with certainty flow away unhindered through the delivery valves.

The described form of construction makes it possible to provide a guide at both ends of a piston, whereby the necessary clearance can be reduced to a minimum. The partition can also be inserted without division of the cylinder. The running surfaces of the two pistons can be machined in one operation.

The rings serving to maintain the partition in place in the cylinder may be cut only at one place and be of flexible composition. It is, however, also possible to divide the ring into several segments which may then be inserted in the groove 30 in the cylinder wall without any gaps. In particular when the ring is in several parts a completely gas-tight partition can be provided to separate the two adjacent working spaces.

The invention may be adopted in all possible kinds of compressors, in particular, however, in the scavenging pumps and charging compressors of two-stroke opposed-piston internal combustion engines.

I claim:

1. A compressor comprising at least one cylinder, a partition dividing the cylinder into two working spaces, opposed pistons reciprocating, respectively, in said spaces, means connecting the partition to the cylinder wall, a column extending from the partition into each working space, and a trunk piston extension fitting to each piston, each column being arranged to enter a trunk piston extension and guide the piston.

2. A compressor according to claim 1 in which the wall of the cylinder is provided with an annular groove and in which the partition is provided with an annular groove which cooperates with the annular groove in the cylinder wall, ring means in the annular grooves for securing the partition to the cylinder wall, and means press-

ing the ring means into tight engagement with the cylinder wall and the partition forming a tight joint.

3. A compressor according to claim 1 in which the partition is formed of two discs, means connecting the two discs together, the two discs forming an annular disc between them, the cylinder wall having an annular groove cooperating

with the annular groove formed between the partition discs, curved rings in said annular spaces, said curved rings being pressed into tight engagement with the partition discs and with the cylinder wall when the discs are held together by the connecting means.

ERWIN WAEBER.
